SEMITAUTOMATIC SAFETY LIGHTER

Edward R. Anderson, Blackstone, Va.

Application October 30, 1943, Serial No. 508,346

5 Claims. (Cl. 158—10)

This invention relates to a semi-automatic safety lighter and more particularly to a lighter embodying a wick which is adapted to be saturated with a liquid fuel which may be lit and employed for kindling purposes and which automatically extinguishes itself at the conclusion of the kindling operation.

It is the object of the present invention to provide a rugged assembly of comparatively few parts, to obtain a kindling unit which is economical in construction and which may be manipulated easily and conveniently to perform the desired operations with utmost safety and dispatch.

It is a further object of the present invention to provide a semi-automatic safety lighter which may be cocked into a position to permit the initial lighting of a small portion of a wick to produce a small flame, functioning as a pilot light, which flame may be enlarged subsequently by the extension of the wick by the operator after his hands are relieved from the task of striking a match to the wick and which flame is controllable in extent to perform the desired operations as a lighter, preliminary burner, pilot light or the like, and which is automatically extinguishable by the release of the wick by the operator.

It is a further object of the invention to provide a safety lighter embodying a woven fabric wick formed of cloth, asbestos, or analogous materials, which may be shifted to a limited extent for consumption by the flame and which may be replaced conveniently at periodic intervals. The invention also comprehends the use of an auxiliary plunger having a wick wrapped therearound which may be replaced by a similar unit following the substantial consumption of the wick.

It is a further object of the invention to provide a safety lighter having a wick enclosed by a split sleeve which is designed to restrict the area of the flame along a predetermined portion of the peripheral surface of the wick to produce a more efficient flame at a desired point and one which will not smudge and smoke.

It is a further object of the invention to provide a self-sealing arrangement which encloses the wick in a manner to prevent evaporation of the liquid fuel with which the same is impregnated or saturated.

Other objects and purposes will appear from the more detailed description of the invention following hereinafter, taken in conjunction with the accompanying drawing, wherein

Fig. 1 is a perspective view of the improved semi-automatic safety lighter with the intermediate portion thereof broken away shown in its cocked position, preparatory to the firing of a starting light by the application of a lighted match or other flame thereto;

Fig. 2 is a front elevation of the safety lighter;

Fig. 3 is a vertical section of the upper portion of the safety lighter showing the position of the parts when the lighter is cocked in the position shown in Fig. 1;

Fig. 4 is a vertical sectional view of the upper end of the safety lighter when the same is in its sealed and inoperative position;

Fig. 5 is a vertical sectional view with certain parts in elevation of the upper portion of the safety lighter showing a different embodiment of the wick mounting therein;

Fig. 6 is a vertical sectional view of the upper portion of the wick shown in slightly extended position and including the refinement of a split sleeve restricting the area of the flame; and

Fig. 7 is a sectional view along line 7—7 of Fig. 6.

In the drawing is shown a safety lighter formed by a cylindrical tube or casing of uniform diameter and of a length which may be conveniently handled by an operator to apply a flame to industrial burners or large kitchen stoves of the type used in army field service kitchens and the like. A wire plunger 2, having a loop 3 formed at one end thereof serving as a handle therefor, extends through the cylindrical casing 1 and terminates in a bent loop 7 at the opposite end thereof. A fabric or woven wick 5 of asbestos, cotton or any other known wick material, is wrapped or coiled around the end of the wire plunger 2 adjacent the loop 7 and may be retained in place by wire ties 6. This wick is adapted to be saturated with a liquid hydrocarbon fuel, such as gasoline, kerosene and the like, one dip being sufficient for a large number of lightings. The rolled wick fits closely the interior of the casing and is adapted to be ejected

by the upward movement of the wire plunger through the cylindrical casing 1 so that the end portion thereof extending through the open end 4 of the casing may be lit with a lighted match or any other flame, and thereafter the wick may be extended further to produce a larger flame for the purpose of its application to any desired points which are of difficult access with a match directly, as is the case with large ranges, vapor retort burners, or industrial burners.

The invention comprehends the automatic ex-

tinguishment of this flame by the release of the plunger 2 to cause the automatic retraction of the wick into the cylindrical casing, and the extinguishment of the flame is assured by the seating of the fire-quenching member 10 upon the open end 4 of the cylindrical casing. The wick is extended from the casing against the force of a coiled spring 20 surrounding a portion of the wire plunger 2 having one end thereof connected to a wire 21 which is anchored to a washer or closure member 8 for the cylindrical casing at the end thereof adjacent the handle. The opposite end of the spring 20 is anchored by a wire 22 to a point of the plunger 2 adjacent to the wick, and this anchor may be conveniently provided by the lower set of tie wires 6 of the wick.

In order to permit the wick to be extended for a slight extent, to permit its initial lighting, and to still leave at least one of the operator's hands free to apply the match thereto, the fire-quenching member at the end of the wick plunger is arranged to permit a cocking of the device to expose the end of the wick without the necessity of holding the wick in this position by hand. This result is attained by arranging a substantially semi-spherical member 11, having a nail 12 extending through the rounded end thereof, functioning as a link, which is looped at 13 to engage the loop 7 at the end of plunger 2. A washer 15 having a diameter greater than the internal diameter of the casing, and preferably one corresponding to at least the external diameter of the casing, is threaded on to the transverse surface of the cylindrical element by means of bolt 16 engaging segments of the sheet metal member 11 which are displaced circumferentially and axially corresponding to the threads of the bolt, in a manner well known in the art of sheet metal nut structures. As shown in Figs. 1 and 3, the link connection between plunger 2 and the fire quenching member 10 at elements 7 and 13 permits a dropping of the washer 10 across a chord of the open end 4 of the casing to maintain the parts in this position by the retractile force of spring 20 acting upon the wire plunger 2. With the parts in this position, an operator can strike a match conveniently on the knurled portion 25 of the casing to ignite the end of the wick 5 protruding from the end 4 of the casing. Thereafter the wick is extended by the ejection of the wire plunger 2 against the force of spring 20 to increase the size of the flame to any desired degree for the purpose of executing the necessary lighting operations.

A release of the handle will automatically guide the wire plunger 2 with the wick thereon and the fire quenching member 10 onto the end of the cylindrical casing to the position shown in Fig. 4 to effectively quench the flame and seal the device against the exit of the combustion gases therefrom. In view of the fact that a manual manipulation of the fire quenching member 10 is necessary to place it in the cocking position shown in Figs. 1 and 2, there is no possibility of the device assuming a position other than that shown in Fig. 4 when the spring 20 retracts the plunger 2 into the casing carrying with it the member 10 freely linked thereto.

It is understood that the position of the wick 5 along the wire 2 may be shifted from time to time as the end thereof is consumed by rearranging the tie wires 6.

Furthermore, the invention comprehends the subdivision of the wire plunger 2 into a main portion 2a and an auxiliary portion 2b upon

which is mounted the wick 5. Loops 28 and 29 are provided on the opposite ends of the auxiliary plunger 2b to engage respectively loop 27 of the main plunger 2a and the loop 13 of the fire quenching member 10. Thereby a used wick unit 5 may be replaced at any time by a replacement unit provided by the auxiliary wire plunger 2b and the wick wrapped therearound. In this constructional embodiment the actuating spring 20 may be anchored by the wire 22 to the loop 27 of the main portion of the plunger, as shown in Fig. 5, or the attachment may be made to loop 28 or some other part of auxiliary plunger 2b.

An additional refinement of the invention may 15 be realized by providing a spring split sleeve 30 upon the end of the wick having a tapering gap 31 to produce a flame of restricted area along the gap. This flame does not smoke as much as a flame burning around the complete periphery 20 of the wick in view of the fact that a lesser amount of fuel is available at the gap for combination with the same quantity of air surrounding the wick. The size of the flame is enlarged by the flared contour of the gap 31 as the wick 25 is extended, as shown in Fig. 6.

A handy embodiment of the invention is attained by a safety lighter using a piece of $\frac{5}{8}$ " pipe or tubing of approximately 2' to $2\frac{1}{2}$ ' in length with a steel wire plunger of about $\frac{1}{8}$ " diameter 30 extending about 4" from the tube in the inoperative position of the lighter. The length of the wick may be 8" or less.

While I have described my invention as embodied in a specific form and as operating in a specific manner for purpose of illustration, it 35 should be understood that I do not limit my invention thereto, since various modifications will suggest themselves to those skilled in the art without departing from the spirit of my invention, the scope of which is set forth in the annexed claims.

I claim:

1. A safety lighter comprising a cylindrical casing, a wire plunger extending through said casing having a handle at one end thereof and a woven wick coiled therearound adjacent the opposite end thereof, a self-seating first-quenching member linked to said wire plunger at said last-mentioned end whereat the wire plunger terminates in a loop, said member comprising a semi-spherical element embodying a substantially semi-spherical portion and a plane end portion, said semi-spherical element having a link extending from the semi-spherical end thereof in engagement with said loop in the end of said wire plunger, and a washer engaging the opposite plane end of said element of slightly larger diameter than the internal diameter of the cylindrical casing, a coil spring surrounding said wire 45 plunger having one end fixed with respect to the end of said casing adjacent said handle and the opposite end attached to a portion of said plunger adjacent to said wick whereby said spring is tensioned in response to the ejecting movement 50 of said wick from said casing for return thereto by the force of said spring, whereupon said fire-quenching member seats itself upon the end of the casing to extinguish any flame thereat.

2. A safety lighter comprising a cylindrical casing, a wire plunger extending through said casing formed with a handle at one end thereof and a fabric wick wrapped therearound adjacent the opposite end thereof, a self-seating fire-quenching member linked to said wire plunger at 55 said last-mentioned end whereat the wire plunger

terminates in a loop, a coil spring surrounding said wire plunger having one end thereof fixed with respect to the end of said casing adjacent said handle and the opposite end thereof attached to a portion of said plunger adjacent to said wick whereby said spring is tensioned in response to the ejecting movement of said wick from said casing for return thereinto by the force of said spring, whereupon said fire-quenching member seats itself upon the end of the casing to extinguish any flame thereat, said self-seating fire-quenching member comprising a semi-spherically shaped element terminating in a plane end portion and fitting into the open end of said cylinder, a link extending from the semi-spherical end of said element in engagement with said loop in the end of said wire plunger and a washer of slightly larger diameter than the internal diameter of the cylindrical casing attached to said element adjacent to said plane portion, said link, semi-spherical element and washer adapted to swivel freely as a unit from the loop of the wire plunger and being of a length slightly greater than the distance of wire and loop of the plunger which is exposed beyond the wick to permit the engagement of the edge of the washer with the open end of said cylindrical casing by the force of said spring to expose the extreme end of said wick for the kindling of a small pilot light for enlargement upon the subsequent ejection of a larger portion of the wick against the force of said spring.

3. The combination set forth in claim 1 wherein said semi-spherical element is formed of sheet metal with the segments thereof at the plane end so disposed as to form a nut unit, and a threaded bolt engaging said nut unit for maintaining the washer in place.

4. A safety lighter comprising a cylindrical casing, a wire plunger extending through said casing having a handle at one end thereof and a woven wick coiled therearound adjacent the opposite end thereof, a self-seating fire-quench-

- ing member linked to said wire plunger at said last-mentioned end, a coil spring surrounding said wire plunger having one end fixed with respect to the end of said casing adjacent said handle and the opposite end attached to a portion of said plunger adjacent to said wick whereby said spring is tensioned in response to the ejecting movement of said wick from said casing for return thereinto by the force of said spring, whereupon said fire-quenching member seats itself upon the end of the casing to extinguish any flame thereat, and a split sleeve surrounding the exposable part of said wick arranged coaxially therewith and forming a gap for confining the flaming area of said wick.
5. A safety lighter comprising a cylindrical casing, a wire plunger extending through said casing formed with a handle at one end thereof and a fabric wick wrapped therearound adjacent the opposite end thereof, a self-seating fire-quenching member linked to said wire plunger at said last-mentioned end, a coil spring surrounding said wire plunger having one end thereof fixed with respect to the end of said casing adjacent said handle and the opposite end thereof attached to a portion of said plunger adjacent to said wick whereby said spring is tensioned in response to the ejecting movement of said wick from said casing for return thereinto by the force of said spring, whereupon said fire-quenching member seats itself upon the end of the casing to extinguish any flame thereat, and a split sleeve surrounding the exposable part of said wick arranged coaxially therewith and forming a gap for confining the flaming area of said wick.
6. A safety lighter comprising a cylindrical casing, a wire plunger extending through said casing having a handle at one end thereof and a woven wick coiled therearound adjacent the opposite end thereof, a self-seating fire-quench-
